UNITED STATES PATENT OFFICE

2,548,660

PLASTIC PANTS FOR INFANTS

Herman Feldman, Forest Hills, N. Y.

Application January 23, 1948, Serial No. 3,940

2 Claims. (Cl. 128—287)

1. This invention relates to baby pants.

More particularly, to baby pants for infants, made of plastic or other suitable material and openable at the crotch.

An object of the present invention is to provide waterproof pants for an infant still wearing diapers, which pants are openable at the crotch to permit the removal of a wet diaper without removal of the pants.

A further object is to provide baby pants as aforesaid, made of a transparent plastic material.

Another object is to provide baby pants as aforesaid in which the flaps of the openable crotch are reinforced by fabric.

Another object is to provide baby pants as aforesaid in which the reinforcing fabric is strong netting providing a non-slip surface.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a front view of a pair of baby pants constructed in accordance with this invention.

Fig. 2 is a view of the pants with the crotch opened.

Fig. 3 is a section on the line 3—3 of Fig. 2.

Fig. 4 is a view, similar to Fig. 1, showing a pair of pants constructed in accordance with a modification of this invention.

Fig. 5 is a fragmentary view of the pants of Fig. 4, showing the crotch opened.

Fig. 6 is a section on the line 6—6 of Fig. 5.

The baby pants, constructed in accordance with this invention, comprises a transparent plastic body 10 of two pieces joined at the front along the seams 11. The waist is bordered by waterproof tape 12 and the leg holes are bordered by waterproof tape 13. Other suitable material may be substituted for the plastic if desired.

The crotch is openable, as aforesaid, as is shown in Fig. 2, so that a wet diaper can be removed through the open crotch when desired. The crotch has a front flap 14 and a depending rear flap 15, the rear flap 15, when the crotch is closed, being folded over the front of the front flap 14.

The front flap 14 is formed as follows: The plastic body has a front depending portion 16 which is folded over rearwardly to form another portion 17, the fold 18 being slightly below the

center line of the leg holes. The fold 18 is horizontal and presents a gently rounded surface. Portion 17 has an arcuate upper edge 19. A piece of strong rough webbing 20 is secured between portions 16 and 17, the webbing 20 having a bottom edge similar to and disposed in the fold 18 and a top edge similar to the edge 19. The webbing 20 is secured at its top and bottom respectively by a row of stitches 21 and 22. The male portions 23 of three snap fasteners are secured in the portions 16—17 and pass through the webbing 20. Instead of snap fasteners any other fastening means may also be used.

The rear flap 15 is formed as follows: The other piece of the body has a depending portion 24. Another sheet of plastic 25 is disposed over the front of portion 24 and a layer of strong rough webbing 26 is disposed between portion 24 and sheet 25. The bottoms of parts 24—25—26 are cut with a pair of scissors to form an arcuate edge 27 and the tops of parts 25—26 are cut horizontally to form a top edge 28. The webbing is sewed to portion 24 and sheet 25 by stitches 29 and the edge 27 is bound by an overcasting stitching 30. Female portions 31 of three snap fasteners are secured to the parts 24—25—26 for coaction with the male snap fastener portions 23.

The operation of the pants is obvious. The three snaps are opened to open the crotch to remove a wet diaper and are closed after a dry diaper has been put on the baby. The webbing sufficiently strengthens the flaps 14 and 15 so that pull on the snaps will not tear the thin plastic of which the pants are made. The webbing is strong and rough, and the holes in it are quite pronounced, causing the plastic to adhere closely to the webbing, preventing the plastic enclosing the webbing from puckering, which puckering, if it occurred, would tend to tear the plastic.

The embodiment of the invention shown in Figs. 4—6 is substantially similar to the embodiment of the invention shown in Figs. 1—3 and like parts are indicated by like reference numerals with a distinguishing accent added. It is distinguished therefrom in that the webbing portions 20 and 26 of the first embodiment have been replaced in the second embodiment by waterproof fabric portions 20' and 26' respectively. Furthermore, a comparison of Figs. 3 and 6 will reveal that the inner portion 25 has been omitted in the embodiment of Fig. 6. This is due to the fact that the waterproof fabric is smooth and does not have the non-slipping function of the webbing. In this figure, the edge 27' is shown to be finished by fusing the fabric portions 24' and

26' together to form a thin edge without any binding.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is.

1. A crotch construction for a pair of baby pants having front and rear panels of plastic material, comprising a front flap depending from the front panel midway of its sides, said front flap having a bottom end portion folded upward along the inner face thereof, a reinforcing web sandwiched between the adjacent faces of the front flap and the upwardly bent bottom end portion, stitches securing said upwardly bent bottom end portion and said web to said front flap, a rear flap depending from the back panel midway of its sides to have its free end portion overlapped and secured to the outer face of said front flap, a reinforcing web extended along the inner face of said rear flap, a sheet of plastic extended along the inner face of said latter reinforcing web, and stitches securing together said rear flap, said latter reinforcing web and said sheet of plastic.

2. A crotch construction for a pair of baby pants having front and rear panels of plastic material, comprising a front flap depending from the front panel midway of its sides, said front flap

having a bottom end portion folded upward along the inner face thereof, a reinforcing web sandwiched between the adjacent faces of the front flap and the upwardly bent bottom end portion, stitches securing said upwardly bent bottom end portion and said web to said front flap, a rear flap depending from the back panel midway of its sides to have its free end portion overlapped and secured to the outer face of said front flap, a reinforcing web extended along the inner face of said rear flap, a sheet of plastic extended along the inner face of said latter reinforcing web, and stitches securing together said rear flap, said latter reinforcing web and said sheet of plastic, fasteners mounted through said front flap, said first-mentioned reinforcing web and said upwardly bent bottom end portion, and complementary fasteners mounted through said rear flap, said latter reinforcing web and said sheet of plastic and engageable with said first-mentioned fasteners for holding said rear flap secured to said front flap.
